CURTAIN ROD AND SUPPORTING MEANS
THEREFOR

Max Kahle, Chicago, Ill.

Application February 23, 1934, Serial No. 712,555

10 Claims. (Cl. 248—263)

This invention relates to curtain rods and supporting means therefor.

One of the objects of the invention is to provide a pair of brackets having a base which is adapted to be attached to a wall. The brackets have formed thereon a supporting arm which has attached thereto a V shaped spring member. A curtain rod is adapted to be mounted on the arm and is provided with a slot in which the spring 10 engages to lock the rod to the arm.

Another object is to provide means for supporting curtain rods which comprises a pair of brackets which have formed thereon a plurality of supporting arms of varied length to facilitate mounting of the rods in parallel thereon.

Another object is to provide a sheet metal bracket having means formed thereon for clamping a spring member thereto.

With these and other objects in view, the invention will be better understood by reference to the following specification and accompanying drawing in which like characters represent corresponding parts and wherein

Fig. 1 is a top plan view of the invention with the brackets attached to a wall and the rods mounted in place, parts being broken away and shown in cross section and

Fig. 2 is a perspective view of one of the brackets.

Referring more particularly to the drawing, 30 1 indicates a bracket having a perforated base portion 2 adapted to be attached to a wall 3 by screws or the like 4. The base 2 in the present instance is rectangular and has arms 5 and 6 bent outwardly at right angles thereto at the longitudinal edges thereof, the arm 6 being substantially longer than the arm 5. The brackets 1 are adapted to be mounted on the wall 3 with the shorter arms 5 arranged inwardly in opposed relation. The arms 5 and 6 are of substantially the same formation and for the purpose of convenience, only one of the arms will be described. Referring to arm 5 it will be seen that the longitudinal edges thereof have U shaped portions 7 35 bent therefrom in opposed relation. Punched from the arm 5 in close proximity to the outer edge thereof is a tongue 8. Mounted longitudinally on the outer face of the arm 5 is a substantially V shaped leaf spring 9 having an inner foot portion 10 and an elongated outer foot portion 11 which are adapted to abut the arm 5. The foot 11 is adapted to be inserted beneath the tongue 8 and be clamped to the arm by a lip 12 formed on the outer end of the arm. The bight portion 13 of the 40 spring 9 is adapted to extend beyond the plane 55

of the outer faces of the portions 7. The portions 7 are rounded off as at 14 to facilitate mounting of curtain rods 15 and 16. The rods 15 and 16 are U shaped in plan and tubular in cross section, the outer ends of the leg portions 17 and 18 thereof respectively being open. Formed in the inner face of the legs 17 are substantially rectangular slots 19, and formed in the outer faces of the legs 18 are adapted to be mounted upon the outer ends of the arms 5 and 6 respectively. The legs 10 are then moved inwardly on the arms until the edges 21 and 22 respectively thereof engage the face 23 of the springs 9. Continued movement of the legs will tend to flatten the spring until the outer edge of the bight portion 13 is in the same 15 plane as the inner face of the walls 24 and 25 of the legs 17 and 18 respectively. The springs remain flattened until the outer edge 19' of the slots 19 and 20 passes the bight portion 13 at which time the spring will move outwardly toward 20 normal position. The rods are moved inwardly until the springs resume their normal position within the slots 19 and 20 at which time the rods 25 will be locked to the arms. It will be noted that the outer edge 19' of the slots 19 and 20 engages the leg 26 of the springs 9 at a point below the center thereof, the result being that movement outwardly of the rods would move the bight portion 13 outwardly thereby limiting movement of the rods.

When it is desired to remove the rods 15 and 16, the springs 9 may be moved toward flattened position by the finger of a person, and the rods withdrawn. If desired, the rods may be made 35 of the telescopic type, thereby necessitating removal of only one end thereof from the brackets when it is desired to arrange a curtain thereon or remove the same.

From the foregoing it will be seen that I have 40 provided a device which is simple in construction and economical to manufacture, and it is to be understood that various changes in the details of construction may be made without departing from the spirit of the invention or the appended claims. 45

Having thus described my invention, what I claim is:

1. In a device of the class described, including a slidable member having a slot therein, a supporting bracket for said member comprising a 50 base, an arm extending at right angles to said base, and a leaf spring carried by said arm having its outer end fixed thereto and the inner end slidably mounted thereon, said spring having a V shaped intermediate portion adapted to be 55

inserted in said slot whereby to lock said member to said bracket.

2. In a device of the class described, including a 5 slidable member having a slot therein, a bracket adapted to support said member comprising a base, an arm bent at right angles to said base having opposed U shaped formations along the longitudinal edges thereof adapted to guide said slidable member, and a leaf spring carried by 10 said arm, having its outer end fixed thereto and the inner end slidably mounted thereon, said spring having a V shaped intermediate portion adapted to be inserted in said slot whereby to lock said slidable member to said arm.
- 15 3. In a device of the class described, a bracket having a base adapted to be attached to a wall, an arm extending at right angles to said base, a spring carried by said arm having its outer end fixed thereto and the inner end slidably mounted 20 thereon, said spring having a V shaped intermediate portion, adapted to receive a slotted tubular rod whereby to lock said rod to said arm.
- 25 4. In a device of the class described, a bracket having a base adapted to be attached to a wall, a pair of parallel arms carried by said base and extending outwardly thereof, a leaf spring carried by each of said arms having its outer end fixed thereto and the inner end slidably mounted 30 thereon, said spring having a V shaped intermediate portion adapted to receive a slotted tubular rod whereby to lock said rod to said arm.
- 35 5. In a device of the class described, a bracket having a base portion adapted to be attached to a wall, a pair of parallel arms extending outwardly at right angles to said base, springs severally mounted on the outer faces of said arms, one of said arms being shorter than the other, each of said springs having one end fixed to its arm and its other end slidably arranged thereon, 40 the intermediate portion of said springs being V shaped and adapted to receive a slotted tubular rod whereby to lock said rod to said arm.
- 45 6. In a device of the class described, a supporting bracket comprising a base, an arm bent outwardly at right angles to said base, a V shaped spring extending laterally lengthwise on said arm and having inner and outer foot portions adapted to engage said arm, a tongue punched from said

arm and adapted to receive therebeneath the intermediate portion of said outer foot, and a lip formed on the outer end of said arm adapted to be clamped against the end of said outer foot.

7. A bracket comprising a base, a pair of parallel arms bent outwardly at right angles from opposite edges of said base, substantially V shaped leaf springs longitudinally mounted on said arms and having inner and outer foot portions adapted to engage said arms, tongues punched from said 10 arms and adapted to receive an intermediate portion of said outer foot portions therebeneath, and a lip formed on the outer end of each of said arms adapted to clamp the respective ends of 15 said outer foot portions to its arm.

8. A bracket comprising a base, a pair of parallel arms bent outwardly at right angles to said base, one of said arms being longer than the other, V shaped leaf springs longitudinally mounted on the face of said arms and having inner and outer foot portions adapted to engage said arms, tongues punched from said arms and adapted to receive an intermediate portion of said outer foot portions therebeneath and a lip formed 20 on the outer end of said arms adapted to clamp 25 said outer foot portions to said arms.

9. A bracket comprising a perforated base, an arm bent at right angles to said base, a V shaped leaf spring mounted on said arm and having inner and outer foot portions extending laterally 30 on said arm, a tongue punched from said arm and adapted to receive the outer of said foot portions therebeneath, and a lip formed on the outer end of said arm adapted to clamp the outer end 35 of said outer foot to said arm.

10. A sheet metal bracket comprising a perforated base, an arm extending at right angles to said base and having opposed U shaped formations along the longitudinal edges thereof, a tongue punched from said arm in close proximity 40 to the outer end thereof, a V shaped leaf spring having inner and outer foot portions mounted longitudinally on said arm, the intermediate portion of said outer foot being adapted to be inserted beneath said tongue, and a lip formed 45 on the outer end of said arm adapted to clamp the outer end of said outer foot to said arm.

MAX KAHLE.
